UNITED STATES PATENT OFFICE

JOHN H. WILHELM, OF ROCKAWAY BEACH, LONG ISLAND, NEW YORK, ASSIGNOR TO
MARKON MANUFACTURING CO., INC., OF NEW YORK, N. Y., A CORPORATION OF NEW
YORK

EYE FRAZING MACHINE

Application filed December 13, 1927. Serial No. 239,727.

This invention relates to an eye frazing machine, that is to a machine for frazing, or milling, the sockets which receive the eyes in doll heads and the like, and an object of the invention is to provide a machine which is adapted to support the doll head or the like and by means of which the frazing operation may be quickly and accurately performed upon the two eye sockets of the head.

A further object is to provide a machine in which only a single frazing tool is employed but embodying means for quickly and accurately moving the doll head from one position to another for bringing the eye sockets of the head into correct register with the single frazing tool.

A further object is to provide a machine as indicated so constructed that it may be readily adjusted for operation upon doll heads or similar articles of different sizes.

A further and more specific object is to provide a machine having a single frazing tool, said machine also including a platform portion or receiving the doll head in a given position thereon, and said platform portion being pivotally mounted to swing into two precise positions with respect to the frazing tool, and to provide spring means operable to hold the platform portion yieldingly in each of said positions.

A further object is to provide a machine as above indicated and in which the frazing of the eye sockets may be performed through the neck opening of the doll head.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:—

Fig. 1 is a top plan view of a machine constructed in accordance with this invention, a portion being broken away and shown in

horizontal section for the disclosure of details.

Fig. 2 is a side elevational view of the structure seen in Fig. 1 and there being illustrated a doll head and supporting means 55 therefor on the platform portion of the machine.

Fig. 3 is a view similar to that seen in Fig. 2 but showing the platform portion swung into operative position with respect to the 60 single frazing tool.

Fig. 4 is a front elevational view of the machine showing the parts thereof in the position seen in Fig. 3, and

Fig. 5 is a view similar to the upper portion of Fig. 3, but being on a somewhat smaller scale and illustrating the manner in which the frazing operation may be performed through the neck opening of a doll head.

Referring to the drawings for describing in detail the structure therein illustrated, the reference character L indicates a base or body portion from which rises a pair of standards as 1 and 2 spaced apart and each of said 75 standards having a bearing opening as 3 at its upper end.

Adjacent these standards is arranged a vertical spindle 4 rotatably mounted in bearings as 5 and 6 carried by the standards, said 80 spindle being adapted to be driven by any suitable means as for instance a drive belt or the like as 7 which engages a pulley 8 fixed upon the spindle.

At its upper end the spindle is provided 85 with a suitable frazing tool as G which of course is so connected with the spindle as to rotate therewith.

Pivottally mounted within the bearings 3—3 of the standards is a carrier 9 upon which in turn is pivotally mounted the platform member H designed for supporting the doll head or other article which is to be operated upon by the frazer G, said platform member being connected with the carrier 9 95 by means of a pivot pin 10 the pivotal axis of which is normally vertical so that the platform is adapted to swing in a horizontal plane between the two positions as indicated by the dotted and full lines in Fig. 1.

Suitable adjustable stops as 11 and 12 are provided for engaging between the platform member and the carrier 9 for determining the limits of movement of the platform member, the stops 11 and 12 in the instance illustrated being carried upon the under-surface of the platform member and arranged to engage the adjacent forward edge surface 13 of the carrier.

10 A handle 14 is arranged at the forward edge of the platform member for convenient manual manipulation of the platform member not only in a horizontal plane but also in a vertical plane as will be presently referred to.

Any appropriate means may be provided for holding the platform member in either of its extreme positions, and for this purpose the drawing illustrates a compression spring 15.

20 This spring is carried upon a slide rod 16 which is pivotally mounted as at 17 upon the platform member by one end and has its opposite end slidably through an abutment member 18 which is pivotally mounted upon the carrier 9 to swing freely about a vertical axis. The spring 15 has one of its ends engaging the abutment 18 and the other end engaging a shoulder 19 provided upon the rod 16.

The pivot 17 is so disposed with respect to 30 the pivot 10 of the platform member that it will move from one side to the other of a straight line between the pivot 10 and the abutment 18 when the platform member is swung horizontally to opposite extremes, and thus the expanding tendency of the spring 15 will always serve to hold the platform member in either of its extremes, and yet the power of the spring may be readily manually overcome by manipulation of handle 14.

40 The platform member H is intended to carry the doll head or other article as 20 which is to be operated upon by the frazer G, and any appropriate means may be employed for defining the position of the head upon the platform so that successive heads may be similarly placed. For this purpose the drawings, Figs. 2 and 3, illustrate a suitable plastic mold or the like as 21 fixed to the platform, and being of a surface contour to exactly 50 conform to the contour of the heads which are to be supported thereon. A spring clamp member as 22, or any other form of retaining means may be used in association with this mold for holding the head temporarily connected therewith.

The relation of the pivot bearings 3 with the frazer is such that when the platform member is swung upwardly within said pivot bearings, as by means of handle 14, one or the other of the eye sockets as 23 of the doll head will be brought against the frazer, according to whether the platform member is in one of its extremes or the other. After the brazing operation has been completed upon the first 55 eye socket the operator has merely to swing

the platform member about the pivot 10 into its opposite position and thereafter again move the head into engagement with the frazer to thus effect the brazing of the second eye socket.

70

It is desirable that suitable means be provided for limiting the extent to which the eye sockets may be pressed against the frazer, and to this end the drawing suggests the use of an adjustable stop device as 24 carried by the standard 2 and disposed to be engaged by an arm as 25 which is fixed to the carrier 9. By this arrangement the operator has merely to continue his pressure of the platform member toward the frazer until the limit of movement is reached as defined by the stops 24-25, and thus all successive brazing operations will be of uniform depth.

80

As hereinbefore suggested it is a feature of this invention to so construct the machine as to adapt it for use upon doll heads or the like of different sizes and to this end the drawings which form a part hereof provide for adjustment of the pivotal support of the carrier 9 with respect to the frazer. The standards 1 and 2 for instance are shown to be provided with a series of bearing openings as 26-26 adjacent the bearing 3, all arranged in a row extending in a general direction radially from the frazer, and the pivot pins or like members as 27 which engage within the bearing openings 3 are yieldable so that they may be readily disengaged from said bearings 3 and moved into engagement with any selected pair of the openings 26-26.

95

By this means the distance of the pivotal mounting for the carrier 9 from the frazer may be varied at will, and hence doll heads or similar articles having openings to be brazed may be readily accommodated although said openings may occur within a wide range of different positions with respect to the platform member.

105

As a simple expedient by which to render the pivot members 27 readily adjustable from bearing opening to bearing opening the drawing suggests, see Fig. 1, that said pivot members may be each provided at the outer end of a rod 28, said rod extending through a cavity as 29 provided upon the carrier 9 and having a handle piece as 30 at its inner end. A compression spring as 31 is arranged within the cavity for urging the rod outwardly and the handle piece is shaped to provide two steps as 32 and 33 co-operative with similar steps which are provided upon the abutting surface of the carrier 9. By these means the pivot members 27 may be readily withdrawn from engagement with the standards 1 and 2 and may be held withdrawn by simple rotary movement of the handle pieces 31 into position with their higher steps engaging the higher steps of the carrier 9. With the pivot members thus held withdrawn the carrier 9 115 may be moved into any desired position and 120

125

130

the handle pieces thereafter moved to allow the pivot members to spring outwardly into the selected pair of bearing openings of the standards, all as will be readily understood from an inspection of the drawings.

5 A suitable form of support is provided as a rest upon which the platform may repose when in its normal inoperative position, as for instance a standard as 34 may be provided upon the base L within the upper end of which is vertically slidable a rod 35, the upper end of said rod being positioned to be engaged by the under-surface of the platform. A suitable set-screw or other retaining member as 36 is provided for holding the rod 35 at any position to which it is adjustably moved to thereby correspond with the different adjustable positions of the carrier within the bearings 3—26.

23 Attention is particularly directed to the fact that by the use of means as herein suggested for definitely defining two positions of the doll head with respect to the frazer it is possible to operate upon any number of 25 doll heads of like size in such manner that the two eye sockets will bear exactly the same relation to each other in all of the heads even though the frazing operations upon the eye sockets are performed individually by a single frazer. The eye sockets of all of the heads will thus be accurately prepared for receiving eye sets all of which are of identical form and proportions.

While this machine may be utilized for use 25 in frazing or milling a plurality of spaced portions of any article it is particularly adaptable, and in fact the structure shown herein is primarily designed, for frazing the two eye sockets of a doll head. The doll head 40 may be a substantially complete head as in Fig. 5 or it may be a half-head as in Figs. 2 and 3, the machine being admirably qualified to perform its frazing operation upon the eye sockets of half-heads regardless of 45 whether the head be placed on the platform with its neck opening toward the operator as in Figs. 2 and 3 or away from the operator as in Fig. 5. When the head is placed upon the platform with the neck opening facing 50 away from the operator as in Fig. 5 it is immaterial whether the head has only a neck opening for admission of the frazing tool G or whether it be a half-head, and here it may be mentioned that one of the most important advantages of the present invention 55 is its ability to operate upon the complete heads having only neck openings for admission of the frazing tool.

The illustration Fig. 5 shows, by means 60 of dot and dash line 37, the relative path of movement of the frazing tool to and from its work through the neck opening 38 of the head, it being borne in mind of course that in the structure illustrated it is the head 65 which moves and not the frazing tool. In

arranging the doll head upon the platform it is simply necessary to so dispose it that the edge walls of the head defining the neck opening 38 clear the frazing tool and allow the head to swing unhindered about the tool to 70 bring the eye sockets of the head against the tool whenever the operating handle is thrown up, it being noted that the platform, with the head, may be as readily swung to its two transverse portions about the pivot 10 here 75 as before.

Adjustment of the pivot pins 27 into any selected pair of bearing openings in the standards 1 and 2 may be resorted to if and whenever found necessary to facilitate the clear 80 swinging of any given size or type of doll head about the frazing tool.

As many changes could be made in this construction without departing from the scope of the invention as defined in the following 85 claims, it is intended that all matter contained in the above description, or shown in the accompanying drawings, shall be interpreted as illustrative only and not in a limiting sense.

Having thus described my invention, what 90 I claim as new and desire to secure by Letters Patent is:—

1. A machine for frazing the two eye sockets of a doll head, said machine comprising a single frazing tool, a carrier pivotally mounted to swing upon a horizontal axis, a work supporting platform connected with said carrier to swing therewith for disposing the work in operative association with said tool, and the connection between the carrier and said work supporting platform being of a character providing for movement of said platform into opposite extreme positions with respect to the carrier for thereby enabling frazing of the two eye sockets successively, together with resilient means to hold said platform into either of its extreme positions. 100

2. A machine for frazing the two eye sockets of a doll head, said machine comprising a single frazing tool, a carrier pivotally mounted to swing upon a horizontal axis, a work supporting platform connected with said carrier to swing therewith for disposing the work in operative association with said tool, and the connection between the carrier and said work supporting platform being of a character providing for movement of said platform into opposite extreme positions with respect to the carrier for thereby enabling frazing of the two eye sockets successively, together with resilient means to urge said platform into either of its extreme positions and adjustable stop means for determining said limits. 115

3. A machine for frazing the two eye sockets of a doll head, said machine comprising a single frazing tool, a work supporting member pivotally mounted upon the machine to swing with respect to the tool for thereby disposing the work into operative engagement 125 130

with the tool, and means whereby said supporting member is adjustable to alter the position of the pivotal axis thereof with respect to the tool.

5. A machine for brazing the two eye sockets of a doll head, said machine comprising a single brazing tool, a work supporting member pivotally mounted upon the machine to swing with respect to the tool for thereby disposing the work into operative engagement with the tool, and means whereby said supporting member is adjustable to alter the position of the pivotal axis thereof with respect to the tool, together with a rest for said supporting member adjustable to accommodate different positions of the supporting member.

6. A machine for brazing the two eye sockets of a doll head, said machine comprising a single brazing tool, a carrier for the work, a pair of standards each having a plurality of bearings provided therein, pivot members for engaging within selected ones of said bearings by which said carrier is pivotally mounted to enable movement of the work into and out of operative engagement with said tool, and means whereby said pivot members may be readily disengaged from said bearings for transfer to other selected bearings at will.

30. 6. A machine for brazing an eye socket of a doll head wherein the brazing operation is to be performed through the neck opening of the head, said machine comprising a brazing tool, a movable carrier; means by which to support the head upon the carrier so that movement of the carrier will cause the tool to pass relatively through the neck opening of the head and to its work upon the eye socket of the head.

40. 7. A machine for brazing the two eye sockets of a doll head wherein the brazing operation is to be performed through the neck opening of the head, said machine comprising a single brazing tool, a movable carrier; means by which to support the head upon the carrier so that movement of the carrier will cause the tool to pass relatively through the neck opening of the head, and the carrier comprising also means by which the head may be moved otherwise with respect to the tool for disposing the head so that the tool will operate upon the eye sockets successively.

8. A machine for brazing an eye socket of a doll head wherein the brazing operation is to be performed through the neck opening of the head, said machine comprising a brazing tool, and a carrier for the head, means by which said carrier is pivotally mounted to swing the head over the brazing tool so that said tool will pass relatively through the neck opening of the head and to its work upon the eye socket of the head, and means whereby the pivotal axis of said carrier may be altered at will with respect to the tool.

35. 9. A machine for brazing the two spaced

eye sockets of a doll head, said machine comprising a single brazing tool, a carrier for the doll head movable into two different positions, movement of the carrier into one of its positions being of a character to dispose one of the eye sockets of the head into operative engagement with the brazing tool, and movement of the carrier into its other position being of a character to move the head for disposing the other eye socket into operative engagement with said brazing tool.

10. A machine for brazing the two spaced eye sockets of a doll head, said machine comprising a single brazing tool, a doll head carrier, and means by which the carrier is pivotally mounted to swing about one axis to and from the brazing tool and about another axis at an angle to the first axis to dispose one or the other of said eye sockets for engagement by said tool selectively at will, together with means engaging the doll head to hold it in position upon said carrier and a handle by which to manually manipulate said carrier.

11. A machine for brazing the two spaced eye sockets of a doll head, said machine comprising a single brazing tool, a carrier for the doll head, manually operable means whereby said carrier is selectively movable into two different positions required for disposing the eye sockets selectively into operative engagement with the tool, and snap acting means to urge the carrier into either selected position.

12. A machine for brazing the two spaced eye sockets of a doll head, said machine comprising a vertically disposed spindle, means by which said spindle is rotatably mounted to rotate upon a vertical axis, a brazing tool fixed to the upper end of said spindle to rotate therewith, a normally horizontally disposed carrier adjacent said brazing tool, means by which said carrier is pivotally supported to swing about a horizontal axis, a work supporting platform also normally horizontal, means by which said work supporting platform is pivotally connected with said carrier to swing with respect thereto about an axis at right angles to said first mentioned axis, means by which to define the position of a doll head supported upon said platform, the pivotal mounting of said carrier being of a character to enable swinging movement of the head into and out of proximity with said brazing tool, and the pivotal mounting of the platform upon the carrier being of a character to enable selective engagement of the eye sockets of the head with the brazing tool.

In testimony whereof I affix my signature.
JOHN H. WILHELM.
